UNITED STATES PATENT OFFICE.

WILLIAM LUTHER HANE, OF OCALA, FLORIDA.

COMBINATION TOOL-HOLDER.

1,032,898.

Specification of Letters Patent. Patented July 16, 1912.

Application filed March 7, 1912. Serial No. 682,239.

To all whom it may concern:

Be it known that I, WILLIAM L. HANE, a citizen of the United States, residing at Ocala, in the county of Marion and State of Florida, have invented a new and useful Improvement in Combination Tool-Holders, of which the following is a specification.

The object of the invention is to provide a simple inexpensive holder of the character 10 specified, for use with lathe planer and shaper, wherein a single improved implement will perform the functions of three now necessary, and by means of which a great economy in time, and labor is effected.

15 In the drawings, Figure 1 is a perspective view of the improvement. Fig. 2 is a longitudinal section, showing the parts in one position. Fig. 3 is a similar view with the parts in another position, and Fig. 4 is partial longitudinal section, at right angles to Fig. 2.

In the present embodiment of the invention, the shank or handle 1 of the tool holder is slotted at its upper end, transversely, as 25 shown at 2, to form a pair of spaced lugs 2^a; and the holder proper 3 is provided with a reduced lug 4, which is received in the slot. The lug 4 is fan-shaped, and is provided with a transverse opening 5. The 30 outer end of the lug is rounded on the arc of a circle whose center is the opening 5, and the lug has an arc-shaped series of recesses 6 on one face, near the rounded end. The body portion of the holder is provided with 35 an opening 7, for receiving the tool 8, and the said opening is polygonal in cross-section to fit the tool, and is arranged at an angle to the shank 1, and to the lug 4.

The tool is held in place by means of a 40 set screw 9 which is threaded through the body portion of the holder and engages the tool. The holder is also provided with a ledge or lip 10 at one side of one end of the opening 7, against which the face of the 45 tool rests, as shown in Fig. 4.

The holder is provided with a lug or apron 11, extending parallel with the adjacent face of lug 4, and in spaced relation, the said lug or apron seating against the 50 outer side of the shank 1. A screw bolt 12 is passed through registering plain openings in the lug 11 of the holder, the adjacent lug 2^a of the shank 1 and the lug 4, and is threaded into an opening in the other lug 55 2^a of the shank.

A screw 13 is threaded into an opening in

the first-named lug 2 adjacent to the series of openings 6, and is provided with a plain portion 14 for engaging one of the said openings. The screw bolt 12 and the screw 13 have polygonal heads, for receiving a wrench, and the holder may swing laterally with respect to the shank on bolt 12, when the screw 13 is released.

In the use of the device, the tool is adjusted in the proper position in the opening 7, and is held in proper position by means of the screw 9. The upper end of the lug 2^a adjacent to the lower end of opening 7 is beveled, as shown at 15 to permit the tool to 60 pass. After the tool has been placed, if it is desired to incline the tool laterally, the screw 13 is turned out a sufficient distance to release the plain portion 14 from the opening 6 with which it is engaged. The 65 holder may now be moved to either side, swinging on the bolt 12, and when at the desired angle the screw 13 is turned inwardly to engage the plain portion with the opening 6 in register therewith, and the 70 holder is locked in position. The holder may thus be held in alinement with the shank or handle, or inclined toward either side. To adjust the holder, the turning of but one screw is necessary.

85 I claim,

1. A device of the character specified, comprising a handle or shank provided at one end with a transverse slot, a holder provided with a reduced fan shaped lug received in the slot, said lug having a transverse opening and the handle having an opening intersecting the slot, and registering with the opening of the lug, the free end of the lug being rounded on the arc of a circle having its center at the transverse opening, said lug having an arc-shaped series of recesses in one face, the holder having a second lug extending parallel with the face of the lug provided with the recesses and in 90 spaced relation, the second lug having an opening registering with the transverse opening of the lug, a screw bolt having a plain portion passing through the openings of the lug and having a threaded portion 95 engaging the handle, and a screw threaded through the handle and having a plain portion at its inner end for engaging one of the recesses.

2. A device of the character specified, comprising a shank or handle having a transverse slot at one end, a holder for the

tool provided with a pair of substantially parallel spaced lugs, one of the lugs being fan-shaped and entering the slot, the other lug overlying the face of the handle, a 5 screw bolt having a plain portion passing through the lugs and a threaded portion at the end remote from the head engaging the handle, said fan-shaped lug having an arc-shaped series of recesses in the face adjacent to the other lug, a screw threaded into 10 the handle and having a plain portion for engaging a recess.

3. A device of the character specified, comprising a shank or handle provided at 15 one end with a transverse recess, a holder having means for receiving a tool and provided with a substantially fan-shaped lug received in the recess, a bolt pivotally connecting the holder and the handle, said bolt 20 passing through the lug, said lug having a series of recesses in one face arranged on the arc of a circle having its center at the bolt, and a screw threaded through the handle for engaging one of the recesses.

25 4. A device of the character specified, comprising a shank or handle and a holder

for the tool, said shank having a transverse recess at one end and the holder having a lug received in the recess and of greater width than the shank, a pivotal connection 30 between the handle and the lug for permitting the holder to swing to either side of the shank, the lug having a series of recesses in one face arranged on the arc of a circle having its center at the pivotal connection, and 35 a screw threaded through the handle for engaging one of the openings.

5. A device of the character specified, comprising a shank or handle and a holder for the tool, said shank having a transverse 40 recess at one end and the holder having a lug received in the recess and of greater width than the shank, a pivotal connection between the handle and the lug for permitting the holder to swing to either side of the shank, and means for holding the holder in 45 adjusted position.
